STETHOSCOPE WITH ROTATABLE BELL

Filed Jan. 21, 1949

UNITED STATES PATENT OFFICE

2,515,471

STETHOSCOPE WITH ROTATABLE BELL

Wilford J. Ratzan, New York, N. Y.

Application January 21, 1949, Serial No. 71,867

4 Claims. (Cl. 181—24)

1

This invention relates to an obstetrical stethoscope with rotatable bell for listening to the fetal heartbeat.

The administration of caudal analgesia in obstetrical cases requires that the patient lie in lateral Sims position. In this position, approximately half of the lateral aspect of the patient's abdomen faces, and is almost in contact with, the bed on which the patient lies. All available stethoscopic instruments designed for listening to the fetal heartbeat are provided with fixed, rigid diaphragm housings which cannot be applied to that section of the abdomen which faces the bed. By sheer force of necessity, therefore, many obstetricians refrain even from attempting to listen to the fetal heartbeat when the patient is in labor with caudal analgesia. Accurate information regarding the state of the fetus is accordingly unavailable.

The stethoscopic instrument comprising the present invention is provided with a diaphragm housing which is adapted to swivel an angular distance of well over 300°. This swivelling feature renders it a very simple matter to apply the diaphragm housing to any part of the patient's abdomen, including those parts which lie closest to the bed. The obstetrician is thereby enabled to listen to the fetal heart regardless of its location.

It is accordingly the principal object of this invention to provide a stethoscope of the character described which is adapted, by reason of its swivelly connected and mounted diaphragm housing, to reach any and all parts of the patient's abdomen, irrespective of the patient's position on the bed on which she lies. It follows of course, that the instrument is equally adaptable for use in other than obstetrical conditions and with respect to other than obstetrical patients. In many cases the patient is immobilized in a position which precludes the application of a conventional stethoscopic instrument. The stethoscope herein claimed will succeed where the conventional instrument fails.

It is accordingly another object of the present invention to provide a stethoscope which has greater versatility than conventional stethoscopes and which is applicable to areas which are now generally regarded as being inaccessible to conventional stethoscopes. Although the generic

name of the instrument herein claimed is "stethoscope" and it may be used wherever the use of a conventional stethoscope is indicated, it may more specifically be termed a "fetoscope" as well as a "caudoscope" because it is especially applicable for listening to the fetal heartbeat, particularly when the patient is in labor with caudal analgesia.

A further object of this invention is the provision of an attachment or accessory for conventional stethoscopes which adapts such stethoscopes for listening to the fetal heartbeat in the difficult cases above mentioned. The attachment herein claimed is very readily attachable to conventional stethoscopes by simply removing the chest piece therefrom and substituting the attachment. The attachment may just as readily be removed from these conventional stethoscopes and the chest piece replaced thereon.

20 A preferred form of this invention is shown in the accompanying drawing, in which:

Fig. 1 is a plan view of the entire instrument.

Fig. 2 is a plan view of the attachment proper which may be mounted on a conventional stethoscope.

Fig. 3 is a side view thereof.

Fig. 4 is a sectional view therethrough, in enlarged, detailed form.

Fig. 5 is a plan view of the diaphragm housing.

Fig. 6 is a transverse section therethrough as well as a longitudinal section through the tubing on which it is mounted.

Fig. 7 is a side view of said diaphragm housing, showing part of the tubing on which it is mounted.

Fig. 8 is a front or face view of said diaphragm housing, showing the diaphragm and part of the tubing which supports the housing.

The instrument herein claimed includes the following conventional parts of a conventional stethoscope: ear pieces 10, metal tubing 11 connected to said ear pieces, rubber tubing 12 connected to the metal tubing, a Y-shaped tubular fitting 13 which is generally made of metal and which is connected at its two upper ends to rubber tubing 12, rubber tubing 14 which is connected to the lower end of said Y-shaped fitting and a coupling 15 which is connected to the free end of said rubber tubing 14. Thus far the instrument is conventional and

all it lacks to complete it is a diaphragm housing, including a diaphragm. It is the attachment thereto, which is in substitution of a conventional diaphragm housing, that constitutes the invention forming the subject matter of the present application.

The attachment herein claimed includes a relatively long tubular arm 20 which is attached at one end to coupling 15. A substantially disc-shaped finger piece 21, with opposed concave sides, is formed on said tubular arm, intermediate its ends. At the opposite end, tubular arm 20 is offset to form a loop 22 whose end portion 23 is disposed on a line which is intersected at right angles by the line on which the non-looped portion of the tubular arm lies. Swivelly mounted on end portion 23 of the tubular arm is the diaphragm housing 30. This diaphragm housing is substantially bell-shaped, being closed at its upper smaller end and open at its lower larger end. A flanged ring 31 is screwed to the larger open end of the bell-shaped housing to hold the diaphragm 32 in its proper position across the opening of said larger end of the diaphragm housing.

A small tapped hole 35 is formed in the top of said bell-shaped housing, eccentrically thereof. Transversely extending end portion 23 of the tubular arm extends into the upper end of the bell-shaped housing through a centrally extending hole which is normal to the longitudinal axis of said bell-shaped housing. It will be noted that an annular groove 37 is formed on said inwardly extending portion of the tubular arm. It will also be noted that a thumb screw 38 having a tapered end 39 is threaded into tapped hole 35 to bring its said tapered end into engagement with annular groove 37 of said transverse end portion 23 of the tubular arm. This inter-engagement of the tapered screw with the groove serves two purposes: it prevents disengagement of said bell-shaped diaphragm housing from the tubular arm on which it is mounted, and it also provides a clamping action whereby said housing may be fixed in any desired angular position relative to said tubular arm.

The use of an annular groove on the end portion of the tubular arm and a tapered screw in the diaphragm housing to engage said groove enables the diaphragm housing to swivel about said end portion of the tubular arm virtually a full 360°. The only thing that stands in the way of a complete circling movement of the diaphragm housing relative to said end portion of the tubular arm is the engagement of ring 31 with loop portion 22 of the tubular arm. Housing 30 is enabled to swivel in either direction on tubular end portion 23 until its diaphragm holding ring 31 strikes the looped portion 22 of said tubular arm. See Figs. 7 and 8. Finger piece 21 is provided on the tubular arm to facilitate handling and manipulating said arm for the purpose of maneuvering the diaphragm housing into proper position relative to the body of the patient.

It will be apparent from the foregoing that the diaphragm housing may be clamped in virtually every useful position on tubular arm 20. It will, therefore, be clear that said diaphragm housing may be applied to virtually every part of the trunk of the human body, irrespective of the position in which it may be encountered.

An extremely important feature of the present invention lies in the fact that the relationship between the diaphragm housing and the

end portion of the tubular arm remains constant and unchanging regardless of the angular position of said housing on said end portion. The reason is clear: said tubular end portion extends into the housing on a line which intersects the longitudinal axis of the housing, at right angles thereto. It is immaterial, therefore, what position the housing happens to occupy relative to said tubular end portion since the relationship of the longitudinal axis of said housing to said tubular end portion remains the same. Hence it is that the stethoscopic properties and qualities of the instrument remain constant, irrespective of the position in which the diaphragm housing is held.

The several parts of the attachment last above described are made, preferably, of metal such as stainless steel. Other materials may be found to be equally useful.

20 It will be appreciated that the foregoing is descriptive of a preferred form of this invention and that said form may be modified in various ways within the broad scope and spirit of the invention.

25 Having thus described my invention, what I claim as new and desire to secure by Letters Patent, is:

1. A stethoscope of the character described comprising ear pieces, tubular sound conduits 30 connected to said ear pieces, a tubular sound-conducting arm connected to said conduits, said arm having an end portion which extends at right angles to the longitudinal axis of the arm, and a diaphragm housing swivelly connected to 35 said end portion of the tubular arm, an annular groove being formed in said end portion of the tubular arm and a screw having a tapered extension engaging said annular groove being provided in said diaphragm housing, whereby 40 disengagement of said housing from said end portion of the tubular arm is prevented and the housing may be clamped in any selected angular position about said end portion of the tubular arm.

45 2. A stethoscope of the character described comprising ear pieces, tubular sound conduits connected to said ear pieces, a tubular sound-conducting arm connected to said conduits, said arm having a looped end portion which extends 50 across the longitudinal axis of the arm at right angles thereto, and a bell-shaped diaphragm housing having a closed upper end and an open lower end, said bell-shaped housing having a hole to receive the end portion of the tubular 55 arm at right angles to the longitudinal axis of said bell-shaped housing, said tubular arm having an annular groove around its end portion and said housing being turnable on said end portion, means to prevent separation of said housing from said tubular arm, said means comprising a screw having a tapered end extending into said housing parallel to the axis thereof, and having interfitting engagement with said annular groove whereby to provide a clamping 60 action against said end portion of the tubular arm to adjustably fix the angular position of said diaphragm housing relative to said tubular arm.

70 3. A stethoscope in accordance with claim 2 in which the tubular arm is provided with a finger piece formed thereon intermediate its ends to facilitate turning and handling said tubular arm for properly positioning the diaphragm housing relative to the patient.

4. A stethoscope attachment comprising a tubular sound-conducting arm having a looped end portion which extends across the longitudinal axis of the arm at right angles thereto and a bell-shaped diaphragm housing which is swivelly mounted on said end portion of the tubular arm for swivelling movement about an axis which is normal to the longitudinal axis of the tubular arm, an annular groove being formed on said end portion of the tubular arm and a screw having a tapered extension being provided in said diaphragm housing for engagement with said annular groove to prevent disengagement of said diaphragm housing from said end portion of the tubular arm and to provide clamping engagement therebetween to adjustably fix

the angular position of said diaphragm housing relative to said end portion of the tubular arm.
